CLAIM

The ornamental design for a skin cover for game console, as shown and described.

DESCRIPTION

The sole FIGURE is a front elevation view of a skin cover for game console showing my new design.

The solid line around the large rounded rectangle in the FIGURE shows a cut line and indicates a separate piece of the skin cover. The claim is directed to the collective appearance of the skin cover for game console shown in the figure. The parts of the skin cover are arranged on the drawing sheet for the convenience of illustration, and the relative positioning of the skin cover forms no part of the claimed design.
